D11-58. OR D14,012 EX

DESIGN

E.W. TUFFLEY

No. 14,012 JEWELRY.

June 26, 1883.

UNITED STATES PATENT OFFICE.

EDWARD W. TUFFLEY, OF BROOKLYN, NEW YORK.

DESIGN FOR JEWELRY.

SPECIFICATION forming part of Design No. 14,012, dated June 26, 1883.

Application filed May 11, 1883. Term of patent 7 years.

To all whom it may concern:

Be it known that I, EDWARD WORNHAM TUFFLEY, a subject of the Crown of Great Britain, residing at Brooklyn, in the county of Kings and State of New York, have invented and produced a new and original Design for Use on Jewelry, Plate, Glass, China, and Earthenware, of which the following is a specification, reference being had to the accompanying drawing, forming part thereof.

The drawing is a face view of my new design.

A is a foliated wreath, showing at four equidistant diametrical points crossed flags *a*.

B is a field, dotted at irregular intervals with five-pointed stars *b*.

C is a shield, having in its upper part three five-pointed stars, *d*, and two horizontal bars,

e, one above the other, being parallel, surmounted by scrolls *F*, a coat of mail, *G*, and a two-thirds-displayed raven, *H*, issuing from a ducal coronet, *M*.

What I claim as my new design, and what I desire to secure by Letters Patent, is—

The combination of a foliated wreath, showing at four equidistant diametrical points crossed flags, and of a star-bedotted field, *B*, with a shield, *C*, surmounted by a scroll, *F*, a coat of mail, and a two-thirds-displayed raven issuing from a ducal coronet, as hereinbefore shown and described.

EDWARD WORNHAM TUFFLEY.
